(57) CLAIM

The ornamental design for a sauce cup, as shown and described.

DESCRIPTION

FIG. 1 is a perspective view of a sauce cup showing our new design;

FIG. 2 is a rear elevational view thereof;

FIG. 3 is a side elevational view thereof;

FIG. 4 is a top plan view thereof;

FIG. 5 is a front elevational view thereof; and,

FIG. 6 is a bottom plan view thereof.

The broken lines in the drawings are included for the purpose of illustration and form no part of the claimed design.
